BAG TYING APPARATUS

August Rolfe, Mattituck, N. Y.

Application November 20, 1953, Serial No. 393,323

3 Claims. (Cl. 53—135)

This invention relates to improvements in bag tying machines and more especially to a machine of this type which will crimp the neck of a bag and then when a wire tie is positioned around the neck of the bag, twist the wire-tie to firmly close the neck of the bag to retain the same in closed position.

The machine is adapted to operate upon filled bags, but some bags are adapted to have the neck thereof tied when empty so that they can be later filled.

The machine provides means for crimping the neck of the bag so that the wire-tie may be placed about the crimped neck and connected to a twisting means that will then twist the wire-tie about the crimped neck.

The machine is adapted to be used with straight wire ties having loops at the ends thereof and the twisting means is to be engaged with each of the loops for the twisting of the wire-tie.

An object of the invention therefore is to provide a machine of this type for crimping and closing open mouth bags so that a wire tie may be twisted about the closed or crimped mouth to retain the same in closed position.

Another object of the invention is to provide a machine of this type that is operated manually by a foot and a hand of the operator.

A further object of the invention is to provide a machine of this type that will operate on bags of various sizes, whether in filled or empty condition.

Further objects of the invention will be apparent as the description of the invention proceeds and when accompanied by the drawings in which:

Fig. 1 is a front elevational view of a machine embodying the invention;

Fig. 2 is a side elevational view of the same;

Fig. 3 is a top plan view of the machine partly broken away showing a bag in position to have the neck thereof crimped or closed;

Fig. 4 is a similar view partly in section and partly broken away showing the neck of the bag in crimped or closed position with the twisted wire tie in position;

Fig. 5 is an enlarged vertical sectional view partly broken away of the wire twisting mechanism of the machine;

Fig. 6 is an enlarged detailed vertical sectional view of the wire twisting mechanism with the same moved to a 90 degree angle from its position in Fig. 5;

Fig. 7 is an elevational view of the machine showing a small bag supporting platform in position thereon;

Fig. 8 is a perspective view of the platform per se; and

Fig. 9 is a perspective view of the wire tie twister in position to receive the loops of the wire-tie.

Referring more in detail to the drawings wherein like parts are indicated by like reference numerals, the machine embodying the invention comprises a rectangular shaped table 10 that is fixed to a similar shaped supporting frame 11. The frame 11 being retained in elevated position by means of the vertically disposed legs 12. A leg 12 being fixed to each corner of the frame 11, as shown in Figs. 1 and 2 and a circular shaped base plate 13 is

2

fixed to the lower end of each leg whereby the legs may be fixed to the floor or similar support.

Extending upwardly from the table 10 and fixed thereto adjacent each of the sides and centrally thereof are a pair of vertically disposed uprights or standards 14. Fixed to and just below the upper ends of the uprights 14 is an arcuate supporting member 15 and secured to the uprights at its opposite ends is an arcuate shaped brace member 16. The brace member 16 being parallel to the supporting member 15 and spaced slightly from the table 10 by means of the short upright 14', which is secured at its ends to the brace member 16 and table 10, respectively. The uprights 14 are of tubular formation and the upper ends are left open for a purpose later to be described.

15 Fixed at its lower end to one corner of the table 10 and extending upwardly therefrom in vertical relation thereto and parallel with one of the uprights 14 is a third upright or standard 17. The upright 17 being secured to the supporting member 15 and brace member 16 by means of connector plates 18.

The under surface of the supporting member 15 has fixed thereto a depending apertured projection or boss 19 and fixed to the upper surface of the brace member 16 in vertical alinement with the projection 19 is a similar upwardly extending apertured projection 20.

25 Secured at their opposite ends to the projections 19 and 20 by means of fastening means 21 are a pair of parallel relatively spaced guide bars 22.

30 Fixed to the inner surface of the upright 17 adjacent the top thereof are a pair of relatively spaced parallel apertured ears 23 and positioned immediately below the ears 23, but spaced therefrom and in vertical alinement therewith, are a similar pair of relatively spaced parallel apertured ears 24. Pivotally connected at one end thereof 35 to the ears 23, by means of a fastener 25, is a link 26 and pivotally connected at one end thereof to the ears 24, by means of a fastener 27, is a similar link 28.

A hand-operated lever 29 is positioned between the guide bars 22 and the lever 29 has an extension 30 on one end 40 thereof which extends at right angles to the longitudinal plane of the lever 29.

The lower end of the extension 30 has a pair of relatively spaced parallel apertured ears 31 secured thereto and the opposite end of the link 28 is pivotally connected to 45 the ears 31 by means of the fastening means 32. The end of the lever 29, at its emergence with the upper end of the extension 30, has secured thereto a similar pair of relatively spaced apertured ears 31' which are in vertical alinement with the ears 31. Pivotally connected to the ears 31', by means of fastening means 33, is the opposite end of the link 26. Pivotally connected to the opposite end of the lever 29, by means of the fastening means 34, 50 is the bifurcated end 35 of the push bar 36 and the upper end of the bar 36 has fixed thereto a circular hand-engaging plate 37.

55 Fixed to the medial portion of the upper surface of the supporting member 15, by screws 38, is a short arcuate shaped plate 39. Secured to the top of the plate 39, in vertical alinement therewith, is a short tubular housing 40 and on the upper end of the housing 40, there is mounted at right angles thereto a rectangular shaped supporting plate 41. Extending upwardly from the plate 41, in vertical alinement with the housing 40, is a second tubular housing 42 and a flange 43 on the lower end of the housing 42 providing means whereby the housing 42 is secured to the plate 41 by fastening means 44. There is an opening 45 in the plate 41 that provides direct communication between the housings 40 and 42 respectively.

60 Mounted for reciprocation in the housings 40 and 42 and passing through the opening 45 in the plate 41 is the operating rod 46. Midway of the rod there is an abut-

ment 47 against which one end of the spring 48 abuts. The lower end of the rod 46, below the abutment 47, is threaded at 49 to receive a guide block 50 and the opposite end of the spring 48 abuts the member 15. The guide block 50 is slotted at 51 to slidably receive the lever 29 and pin shafts 52 journal the rollers 53 in the slot 51 for rolling engagement with the lever 29.

The upper end of the rod 46 above the abutment 47 is provided with a rack 54 which engages a pinion 55. The pinion 55 is mounted in a small semi-circular housing 56 which is formed integral with the housing 42 and communicates therewith. The pinion 55 is fixed to a shaft 57 which extends forwardly of the housing 42 to lie in a position above and parallel to the plate 41. Collars 58 are secured to the shaft 57 on opposite sides of the housing 56 and the collars abutting the housing 56 serve to retain the pinion in engagement with the rack 54.

Forwardly of the housing 42 adjacent the outer end of the plate 41, there is secured to the plate 41, by a fastener 59, a bearing housing 60 in which the shaft 57 is journaled.

On the forward end of the shaft 57, there is a removable chuck 61 which is adapted to retain an S-shaped wire tie twister 62 therein.

The operational elements previously described form 25 the wire tie twisting portion of the invention and the operation of the same will be later described.

Secured to the rear surface of the supporting member 15 and brace member 16, at the medial portions thereof, is a pair of substantially arcuate shaped guide bar members 63. Pivotaly mounted intermediate of the members 63, by a pivot pin 64, is a substantially L-shaped foot operated lever 65. A circular foot pedal plate 66 is secured to the end of the lever 65 that extends forwardly of the legs 12.

Secured to the opposite end of the lever 65, at right angles thereto, to provide a T formation, is a short bar 67 and openings 68 are provided at opposite ends of the bar 67 to receive the hooked ends 69 of the finger operating links 70. Cotter pins 71 retain the ends 69 in the openings 68. The opposite ends of the links 70 are also hook shaped, as at 72, and the ends 72 are received in openings 73 in the projections 74 on the substantially S-shaped fingers 75. On one of the ends of each finger 75 is a bearing 76 which is journaled in the bearing housing 77 by means of the bearing screw 78. The bearing housings 77 being mounted at opposite sides of the enlarged end portion 79 of the plate 41.

In Fig. 3 the fingers 75 are shown in non-operative position and a spring 80 connected at one end to the eye 81 fixed to the under surface of the frame 11 and at the opposite end to the opening 81' in the foot lever 65, retains the fingers in this position.

The operational elements previously described form the neck closing or crimping portion of the invention and the operation of the same will be later described.

In Fig. 7 there is shown in operational position with relation to the apparatus an elevated platform or seat 82. The platform 82 is of circular formation, as shown in Fig. 8, and secured to the rear edge for a portion thereof and at right angles thereto, is a band 83. S-shaped supporting members 84 are secured at one end portion to the under surface of the platform 82 at the front ends of the band 83 and lugs 85 depending below the opposite end portions of the S-shaped supporting members 84 are positioned in the open upper ends of the uprights 14 to retain the platform 82 in the position shown in Fig. 7.

In the operation of the device a bag B is positioned on the table 10 so that the open mouth thereof extends upwardly beyond the fingers 75, as shown in Fig. 3. The operator of the machine then places a foot on the pedal 66 and then pushes downwardly and forwardly thereon. Such action causes the lever 65 to pivot on the pin 64 causing the upper end of the lever 65 to move in a forward direction. Forward movement of the lever 65 carries 75

the bar 67 secured thereto from the position shown in Fig. 3 to the position shown in Fig. 4. This action results in the forward movement of the links 70, causing the fingers 75 to move from the position shown in Fig. 3 to the position shown in Fig. 4. At this time the fingers have crimped or closed the mouth of the bag B.

A wire tie 85' having a loop 86 at each end is then positioned around the neck of the bag, as shown in Fig. 9. The loops 86 are then engaged with the opposite ends of the wire twister 62.

A hand of the operator is then placed on the plate 37 and downward pressure on the plate 37 causes the downward movement of the lever 29. This action causes the lever 29 to pull the rod 46 downwardly by reason of the engagement of the lever 29 with the rollers 53. The rollers 53 journaled in the guide block 50 which is secured to the rod 46 cause the downward movement thereof.

The downward movement of the rod 46 and the rack 54 causes the pinion 55 to be rotated. Rotation of the pinion 55 causes rotation of the shaft 57 to which the pinion is secured. Rotation of the shaft 57 causes the chuck 61 and wire tie twister 62 to rotate, twisting the wire tie about the neck of the bag B.

Upon release of the pressure on the plate 37 the lever 29 will move upwardly through the action of the spring 48 causing the wire twister 62 to rotate in the opposite direction to be released from the wire tie 85'.

The operator then moves his foot from the pedal 66 and the spring 80 will then return the fingers from the position shown in Fig. 4 to the position shown in Fig. 3.

The bag can then be removed from its position. If the bag is of large size, it can be positioned on the table 10, but if the bags to be tied are small in size the table shown in Fig. 8 is positioned as in Fig. 7. Thus the neck of the small bags can be closed and tied as previously described.

From the foregoing description, when taken in connection with the accompanying drawings, the advantages of the construction and the method of operation will be readily apparent to those skilled in the art to which the invention pertains and while the principles of operation of the invention as applied to these embodiments of the invention has been duly described, it is to be understood that the embodiment as shown is merely illustrative and that various and sundry changes or modifications may be made as desired in the construction without departing from the spirit of the invention and the scope of the appended claims.

Having thus described the invention what I claim as new and desire to be secured by Letters Patent is:

1. In a bag crimping and tying apparatus, an elevated table, vertically disposed uprights mounted on said table, supporting and brace members connected to said uprights, parallel guide means secured intermediate of said supporting and brace members, a hand operated lever pivotally mounted on one of said uprights and extending intermediate of said guide means, a wire tie twisting means mounted on said supporting member and operatively connected to said lever, said wire tie twisting means comprising a vertically disposed rod connected to said lever, said rod having a rack portion thereon, a shaft extending at right angles to said rod and having a pinion on one end to coact with the rack on said rod, and a wire tie twister on the opposite end.

2. A bag crimping and tying apparatus as defined by claim 1 wherein a pair of bag crimping fingers are pivotally mounted on said supporting member, and a foot actuated lever pivotally mounted on said apparatus and connected to said crimping fingers for actuating the same.

3. The bag crimping and tying as defined in and by claim 1 wherein a pair of bag crimping fingers are pivotally mounted on said supporting member adjacent said shaft, foot operated lever means mounted on said frame and including a foot pedal extending forwardly under

said table and an operating portion extending upwardly adjacent said supporting member, and a pair of links connecting said operating portion with said crimping fingers for swinging said fingers upon depression of said pedal together and crimp a bag adjacent said wire twister. 5
